UNITED STATES PATENT OFFICE.

DAVID R. KNAPP, OF POTTSVILLE, PENNSYLVANIA, ASSIGNOR TO THE EASTERN STEEL COMPANY, OF POTTSVILLE, PENNSYLVANIA, A CORPORATION OF PENNSYLVANIA.

ELECTRIC FURNACE.

1,240,460.

Specification of Letters Patent. Patented Sept. 18, 1917.

Application filed February 19, 1916. Serial No. 78,351.

To all whom it may concern:

Be it known that I, DAVID R. KNAPP, a citizen of the United States, residing in Pottsville, in the county of Schuylkill and State of Pennsylvania, have invented certain new and useful Improvements in Electric Furnaces, of which the following is a specification.

My invention relates to that class of furnaces known as the induction type used principally for refining steel, and my objects are: first, to provide a furnace whereby the bottom and walls may be repaired without completely discharging the liquid metal; second, to provide a furnace whereby the metal can have a variable sectional area, wherein the minimum area will be constantly changing in a circumferential direction according to predetermined requirements; and third, to provide a furnace wherein the metal can be subjected to an even normally low temperature at which certain undesirable elements can be eliminated, then subjecting the metal to a lower and abnormally high temperature by increasing and decreasing its cross section, using approximately the same rate of power as when subjected to an even normal temperature, and at which said high temperature will eliminate other undesirable elements.

With these objects in view, my invention consists in certain novel features of construction and arrangement of parts, as will hereinafter more fully be described and pointed out in the claims, reference being had to the accompanying drawings forming part thereof, and in which—

Figure 1 is a sectional elevation showing the principal parts. Fig. 2 is a plan partly in section on the line A—B. Fig. 3 is a view showing the trunnion on which the furnace is supported; and Fig. 4 is an elevation showing guides to prevent the furnace from revolving. Fig. 5 is a detail in side elevation showing the guides removed from the path of the furnace spider.

In said figures similar numerals of reference refer to similar parts throughout the several views and in which the numeral 1 designates the iron magnetic circuit energized by the coil 2.

3 designates a circular brick structure of the furnace in which is the annular trough 4

designed to hold the metal to be treated. 55 This construction is a type of induction furnace well known to the art.

5 designates a circular plate as large in diameter as the furnace element and upon which the furnace rests.

6 designates a spider provided with a recessed boss at the bottom thereof and said spider is adapted to support the plate 5 which is fixed thereto.

7 designates a circular element fitted into 65 the said recess and adapted to rotate therein.

9 designates a supporting casting provided with a recessed base and 10 designates a circular rack fixed thereon. The upper portion of said base 9 is pivotally connected 70 to the circular element 7 by the pin 8, shown in Fig. 3.

15 designates a base for the furnace as a whole and said base is provided with the vertical guiding members 16 adapted to embrace the legs of spider 6 to prevent the furnace from rotating during the refining operation.

21 designates a removable securing means for fastening the guides 16 to the base 15. 80 In case the furnace is desired to be revolved the guides 16 could be thrown out so that the spider 6 would disengage therewith. In order to provide for this action, each of the guides 16 is mounted upon a suitable pivot 35 22 and when the guides are in position to prevent movement of the furnace, each is fixed in its upright position by inserting a dowel pin 23 or the like. The removal of the pins 23 allows the guides to be swung 90 to one side and out of the path of the furnace spider 6 as will be readily understood. This movement can be accomplished if desired, for instance, to pour a heat or any portion thereof on any radial line. 95

14 designates a circular element or bearing rigidly fixed to the base 15 and adapted to fit into the recess of the supporting casting 9 which is revolvably mounted thereon.

13 designates a driving shaft supported 100 by the bearing 12, and said driving shaft has the pinion 11 fixed thereon, engaging with said circular rack 10.

19 designates a right hand screw pivotally fixed to the circular element 7, and 20 designates a left hand screw fixed to the supporting casting 9. 105

21 designates a nut in threaded engage-

ment with both screws and adapted to tilt the furnaces by moving the circular element 7 on the pivot pin 8.

17 designates a tapping spout, and 18 5 designates a slag spout as found on metal furnaces.

Having described the various parts throughout the several views its mode of operation will be substantially as follows, 10 all of which will be readily understood by those skilled in the art to which the invention relates:

The furnace being adjusted on a level plane by adjusting the nut 21 the charge is 15 placed in the annular trough 4 at which time the metal will have the same cross section throughout. The coil 2 being sufficiently energized will induce enough current in the circular bath to bring the metal up 20 to a predetermined normally low temperature. This temperature will be sufficiently high to remove, in the case of steel, the undesirable elements of silicon, phosphorus, sulfur and manganese to desirable quantities, 25 but not the carbon, as it is desirable to hold the carbon so that the manganese co-acting with the carbon can remove the sulfur. In order to remove the carbon and bring the metal up to a high temperature the furnace 30 is tilted by adjusting the nut 21 which will increase the area to C—D on one side and reduce the area to E—F on the other side. The resistance of the bath will remain approximately the same, due to increasing the 35 area on one side and decreasing it on the opposite side. Therefore the current will remain the same. The restricted area will now come up to a very high temperature and at the same time power being applied to the 40 shaft 13 will cause the circular element 7, now tilted, to revolve. The furnace being held by the spider 6 and guides 16 from revolving will cause the heated metal to have a wave like motion, increasing each particle 45 to a very high temperature and gradually reducing until the minimum is reached, when the cycle is repeated until the whole bath has been subjected to a high temperature and the desirable results are obtained.

50 It is obvious that the metal now being in motion will bring it in intimate contact with the slag and thus remove further the undesirable elements. The desirable quantity of metal is now tapped through the spout 17, 55 the slag being previously removed through the spout 18. The amount tapped depends how much the furnace is tilted. After sufficient metal has been withdrawn the spout 17 is plugged, the metal remaining serving as a 60 conducting ring of desirable purity for the next charge. The furnace now having its minimum charge can be tilted so to expose the bottom and side walls at the highest point, and by revolving the circular element 65 7 the furnace will again assume the afore-

said motion, thus exposing in one revolution the entire bottom during which time the said bottom and walls can be repaired. The foregoing method pertains to the manufacture of steel in which molten pig iron and 70 slag elements are added to the charge left in the furnace after each operation, through the spout 18, but a cold charge could be added instead of molten pig iron, provided the furnace was provided with suitable doors, 75 thus accomplishing the aforesaid objects of my invention. I do not want to limit myself to the exact structure of the furnace as shown, as it is obvious that certain departures can be made therefrom without departing from the spirit and intent of my 80 said invention and the furnace shown is only by way of example to explain my refining method as well as one form of apparatus for carrying out the same. As far as 85 I am aware, I am the first in the art to devise a method of refining metal wherein one of the steps embodies a variation in the cross-sectional area of the metal being refined in such a manner that with the same 90 rate of power different temperatures may be produced in different parts or strata of the metal and such temperatures definitely controlled in a predetermined manner.

It will further be noted that the step of 95 varying the cross-sectional area of different parts of the same body of metal and thereby producing a high temperature at one part and a low temperature at another part of the metal, is a very important and essential 100 feature of the invention in that it now becomes possible to vary or adjust the area of the metal being refined for a high or low temperature and thus meet different conditions and properties existing in different 105 metals.

Having now described my invention what I claim and desire to protect by Letters Patent is:

1. In an induction furnace of the character described, a fixed base, a supporting casting revolvably mounted on said base, means for rotating said supporting casting, a circular element supported by a trunnion on said supporting casting, means for varying 110 the plane of said circular element, a furnace revolvably mounted on said circular element, and means to prevent the furnace from rotating, substantially as described.

2. In an electric furnace, a crucible or 115 trough for containing a body of metal, means for heating the metal and for varying the cross-sectional area of the metal whereby the temperature of one portion of the metal is raised and the temperature of another 120 portion is lowered and means to adjust the area varying means.

3. In an electric furnace, a crucible or 125 trough mounted for rotary movement and adapted to contain a body of metal, means 130

for heating the metal, means for producing a maximum cross-sectional area of metal at one part of the trough and a minimum cross-sectional area of metal at another part of the trough and means for simultaneously varying the location of said maximum and minimum areas.

4. In an electric furnace, an annular trough mounted for rotary movement and adapted to contain a body of metal to be refined, means for heating said metal, means to prevent rotation of said furnace during the refining operation and means to cause the said metal to vary in cross-sectional area throughout the length of said trough.
5. In an electric furnace, the combination

of a rotatable crucible or trough for containing a body of metal to be refined, means to lock said furnace against rotation, means to produce a circumferentially oscillating movement to said trough in its locked position and means operable at will for releasing said furnace whereby rotary movement may be imparted and the metal discharged in any radial direction. 25

In testimony whereof I have subscribed my name to this specification in the presence of two subscribing witnesses.

DAVID R. KNAPP.
